MAGAZINE RIFLE

Alton Melvin Olson, Seattle, Wash.

Application August 29, 1949, Serial No. 112,880

15 Claims. (Cl. 89—33)

1

This invention relates to magazine rifles of the type embodying a sliding breech bolt, and it provides improved means operated by the breech bolt for loading the magazine and for controlling delivery of successive groups of cartridges from the magazine to the receiver.

According to this invention, an elongated magazine is fixed beneath and disposed longitudinally of the barrel, said magazine opening at its rear end into the receiver and being adapted to contain a plurality of groups of cartridges. Means is provided which is operable by the breech bolt for loading the magazine by forcing successive groups of cartridges into the same from the cartridge receiver. Also, a cartridge lifter is provided for raising the cartridges in the receiver and thereby successively bringing said cartridges into the path of the breech bolt so that the latter may force the successive cartridges forwardly into the firing chamber. Other means are provided for depressing the cartridge lifter upon rearward movement of the breech bolt after the last one of a group of cartridges has been forced from the receiver into the firing chamber, and for releasing a new group of cartridges in the magazine for delivery into the receiver and onto the follower plate of the lifter.

By employment of this invention, an undesirable laterally projecting or depending magazine is avoided, and the rifle may be operated to successively fire the cartridges of a plurality of groups which have been previously placed in the receiver and all but one of which has been forced into the magazine by forward movement of the breech bolt.

The exact nature of the present invention, as well as other objects and features thereof, will become apparent from the following description when considered with the accompanying drawings, in which:

Figure 1 is a top plan view of part of a magazine rifle embodying the present invention, the breech bolt being locked in its forward position;

Figure 2 is a view thereof, partly in side elevation and partly in section with a group of cartridges in the receiver and with the cartridge lifter depressed;

Figure 3 is a view somewhat similar to Figure 2, looking at the opposite side of the rifle;

Figure 4 is a view partly in plan and partly in longitudinal section on the line 4—4 of Figure 3;

Figure 5 is a longitudinal section taken on the line 5—5 of Figure 1, but with the breech bolt retracted;

Figure 6 is an enlarged fragmentary view, part-

2

ly in plan and partly in section on the line 6—6 of Figure 5;

Figure 7 is a view somewhat similar to Figure 3, but with the cartridge lifter fully raised and the breech bolt in its forward position after having forced the last one of a group of cartridges into the firing chamber;

Figure 8 is a view similar to Figure 7 but with the breech bolt nearly retracted and with the cartridge lifter depressed thereby;

Figure 9 is a view somewhat similar to Figure 8 showing the breech bolt in fully retracted position whereby a group of cartridges in the magazine is released, which group has been delivered into the receiver and onto the cartridge lifter;

Figure 10 is an enlarged fragmentary section taken on the line 10—10 of Figure 9;

Figure 11 is a view somewhat similar to Figure 5, but with the cartridge lifter fully depressed, and with the magazine-loading cartridge push bar connected to the breech bolt and shifted forwardly onto the cartridge lifter;

Figure 12 is an enlarged fragmentary section taken on the line 12—12 of Figure 11;

Figure 13 is an enlarged fragmentary transverse section taken on the line 13—13 of Figure 2;

Figure 14 is a longitudinal sectional view of the rifle, partly broken away, showing details of the magazine, the breech bolt being retracted;

Figure 15 is a view partly in side elevation and partly in section, showing the cartridge push bar shifted forwardly by the breech bolt to the position wherein it has forced a group of cartridges into the magazine;

Figure 16 is an enlarged transverse section taken on the line 16—16 of Figure 14; and,

Figure 17 is an enlarged transverse section taken on the line 17—17 of Figure 15.

Referring in detail to the drawings, which show an embodiment of the invention applied to a rifle having a manually operable sliding breech bolt, A is the barrel having a firing chamber —a—, B is the receiver, C is the sliding breech bolt, D is the stock, and E is the forearm.

In accordance with the present invention, an elongated magazine 5 is fixed beneath and disposed longitudinally of the barrel, and is preferably housed in the forearm, as shown. This magazine opens at its rear end into the receiver and is adapted to contain a plurality of groups of cartridges, arranged one behind another and adapted to be successively forced into the magazine from the receiver. A spring catch 6, attached to one side of the receiver, has an inwardly directed free front end 7, that normally projects

through a side slot 8 at the juncture of the receiver and the magazine into the path of the rearmost group of cartridges within said magazine to releasably hold the groups of cartridges within the latter. A follower or plunger 9 is 5 slideable in the magazine and is pressed rearwardly by a helical compression spring 10 surrounding a rod 11 fixed to and projecting forwardly from the follower. A tube 12, fixed to the front end of the magazine and preferably housed in the forearm, is adapted to guide the rod 11 and receive it when the follower is forced forwardly by the cartridges as they are loaded into the magazine. Thus, when the catch 6 is flexed outwardly to withdraw its end 7 from the path 10 of the group of cartridges at the rear end of the magazine, such group of cartridges will be forced into the receiver by the follower. The free end of catch 6 extends through a slot 13 in a second 15 resilient catch 14 whose forward end is movable through slot 8 in front of the end 7 of catch 6. Catch 14 has a reduced outwardly offset shank 15 (Figures 6, 9 and 10) that extends outwardly through a slot 16 of catch 6. A lever 17 is pivoted at one end to catch 6 at 18, and has a cross pin 19 at its free forward end which underlies the shank 15 of catch 14. The forward end of a pull bar 20 is pivoted to a lateral arm 21 of lever 17, and the arrangement is such that when the bar 20 is pulled rearwardly the catch 6 is flexed from the operative position of Figure 6 to the inoperative position of Figure 10 so as to allow the plunger 9 to force a group of cartridges into the receiver. Also, the catch 14 is tensioned so that its free end will spring into the path of the next group of cartridges in the magazine to hold them in the latter (Figure 10) when the first group has passed rearwardly to the receiver. Upon release of the bar 20, the parts return to the position of Figure 6 under the influence of catch 6, the catch 14 being retracted so as to allow the second group to be moved rearwardly from the dotted line position of said Figure 6 to the full line position thereof where they are stopped by the catch 6 which has been projected.

A cartridge lifter is provided to successively raise the cartridges in the receiver and bring them into the path of the breech bolt for being forced by the latter into the chamber —a— upon forward movement of said breech bolt. This lifter consists of a follower plate 22 pivoted to the forward end of a lever 23 which has its rear end pivoted at 24 in the stock D behind the receiver, and which is urged upwardly by a spring 25. Upward movement of lever 23 is limited by a cross pin 26 to a point where the last cartridge in the receiver has been raised into the path of the breech bolt as shown in Figure 7.

Means is provided for depressing the cartridge lifter upon rearward movement of the breech bolt immediately after such cartridge lifter has reached its uppermost position. This means includes a dog 27 pivoted at 28 to the lever 23 and having a short arm connected by a link 29 to one end of spring 25 so that said spring acts to raise the lever 23 and to swing the longer pointed arm of said dog forwardly against the pin 26. The breech bolt C has a notch 30 in the under side thereof, and the arrangement is such that the free end of the pointed arm of the dog is spaced below the breech bolt until the cartridge lifter approaches its uppermost position, whereupon the spring 25 raises lever 23 and dog 27 slightly to engage the free end of said pointed arm of the dog in the notch 30 of the breech bolt upon rearward movement of the latter. Thus, upon con-

tinued rearward movement of the breech bolt, the dog 27 will be swung rearwardly and depressed thereby to depress the cartridge lifter from the position of Figure 7 to that of Figure 8. The pull bar 20 is slidably mounted on the stock at one side of the receiver and has a lateral extension 31 at its rear end arranged in the path of the laterally offset free end portion of the pointed arm of dog 27 as shown in Figures 10 and 12. Thus, after the cartridge lifter has been depressed, final rearward movement of the breech bolt causes the dog 27 to engage the extension 31 and pull the bar 20 rearwardly so as to release the catch 6 and permit the follower 9 to force a group of cartridges into the receiver and onto the follower plate 22 of the cartridge lifter.

Upon subsequent forward movement of the breech bolt, the spring 25 will swing the dog 27 forwardly away from and below said breech bolt, and upon the next rearward movement of said breech bolt, the cartridge lifter will raise this group of cartridges so that the uppermost one thereof will be disposed in the path of said breech bolt for being forced thereby into chamber —a— upon the next forward movement of said breech bolt, as shown in Figure 5. The rest of the cartridges of this group will be similarly fed to the firing chamber by repeating the reciprocation of the breech bolt. Each time the receiver is emptied, a new group of cartridges will be delivered to the same from the magazine as previously described, until the supply of cartridges in the magazine is exhausted. While only three cartridges are shown in each group for the sake of simplicity, it is preferred to construct the rifle so that five cartridges may be provided in each group. Also, the magazine is preferably adapted to receive three groups in addition to one in the receiver. The magazine is arranged so that it does not project in the user's way or depend so as to interfere with firing in a prone position, and the rifle may be readily adapted to receive the groups of cartridges arranged in clips, if desired. Upward movement of the cartridges in the receiver is properly limited by a stop member 32 pivoted at 33 on the stock D at one side of the receiver by means of a spring hinge which normally swings said stop member inwardly to operative position through a slot 34 provided in the frame part 35 in which the breech bolt is slideable. The stop member 32 has a thumb piece 36 by which it may be manually retracted to permit insertion of the cartridges into the receiver through the top of the latter when loading the magazine. Stop member 32 has an oblique edge 37 at its rear side so that the breech bolt will cam said stop member out of its path when said breech bolt is moved forwardly.

The rear portion of the breech bolt is provided with a segmental recess 38 and the forward portion thereof has a longitudinal groove 39 which opens at its rear end into the recess 38. A cross pin 40 carried by the breech bolt extends across the forward end of groove 39. A U-shaped cartridge pusher 41 is disposed within the stock between spaced members of lever 23, and this pusher is movable longitudinally of the rifle forwardly into and rearwardly out of the receiver. The intermediate portion of the pusher is vertically disposed so that the end portions thereof project rearwardly with the upper end portion of the same resting on the bottom of frame part 35 and disposed in the groove 39 of the breech bolt when the latter and said pusher are in their

rearward positions. At the top and near the front thereof, the pusher is provided with a notch 42 adapted to receive the cross pin 49 if the front of the pusher is pressed upwardly when the breech bolt and said pusher are in their rearward positions. Normally, however, the pusher occupies a position with its front end lowered slightly so that the pin 49 is disengaged from the notch 42. In loading the rifle, the breech bolt is first moved rearwardly so as to depress the cartridge lifter as previously explained. The front of the pusher 41 is then pressed upwardly to engage the pin 49 in notch 42 so that when the breech bolt is moved forwardly a short distance, a similar movement is imparted to the 15 pusher and the bottom of the latter rides onto the rear end of the follower plate 22 of the lifter as shown in Figure 11. The stop member 32 is then swung outwardly and a group of cartridges is placed in the receiver upon the depressed follower plate 22. The breech bolt is then moved forwardly all the way so as to correspondingly move the pusher and cause the latter to push the group of cartridges into the 20 magazine where they are held by the catch 6. By limiting the rearward movement of the pusher to the position of Figure 11, this operation may be repeated until the magazine is filled. To so limit the rearward movement of the pusher, a stop element 43 is pivoted on the stock at 44, and is urged by a spring 45 to dispose its front lateral extension 46 behind and in the path of the intermediate portion of the pusher when the latter is shifted forwardly to the position of Figures 11 and 12. After the magazine has 25 been filled, the element 43 may be swung to the position of Figure 10 to permit complete rearward movement of the pusher by the breech bolt until said pusher rides off of the plate 22 and slightly lowers at the front to disengage from the pin 49. The cartridge lifter is then free to raise the cartridges in the receiver, and the breech bolt may be moved forwardly to push successive cartridges into chamber —a— without moving the pusher 41 from its rearward position. When the breech bolt is thus moved to its foremost position, the upper end portion of pusher 41 is located in the recess 38 so that the breech bolt may be turned as usual to lock it in such foremost position while a cartridge is being fired by conventional firing mechanism, not shown. As shown, the breech bolt has a stud 47 engageable in front of a shoulder 48 of the frame part 35 when the breech bolt is so turned in its foremost position.

From the foregoing description, the construction, operation and advantages of this invention will be apparent to those skilled in the art. Modifications and changes in details of construction are contemplated within the spirit of the invention as claimed. Obviously, the invention may be adapted to automatic rifles in which rearward movement of a sliding breech bolt results from recoil upon firing.

Having described the invention, what is 65 claimed as new is:

1. In a rifle including a barrel, a sliding breech bolt, a frame supporting the breech bolt, and a cartridge receiver adapted to receive a group of superimposed cartridges disposed parallel with the barrel, and elongated cartridge magazine arranged longitudinally of the rifle beneath the barrel and opening at its rear end into the receiver, said magazine being adapted to receive a plurality of groups of superimposed cartridges 70

one behind another with said cartridges disposed parallel with the barrel, a pusher operable by the breech bolt for forcing successive groups of cartridges forwardly from the receiver into the magazine upon forward movements of said breech bolt said pusher being slidably carried by the frame under the breech bolt, and means releasably securing said pusher to the breech bolt.

2. In a rifle including a barrel, a sliding breech bolt, and a cartridge receiver adapted to receive a group of superimposed cartridges disposed parallel with the barrel, an elongated magazine arranged longitudinally of the rifle beneath the barrel and opening at its rear end into the receiver, said magazine being adapted to receive a plurality of groups of superimposed cartridges one behind another with the cartridges disposed parallel with the barrel, a catch engageable with the one group of cartridges at the rear of said magazine to releasably hold said groups of cartridges in the magazine, means in the magazine to force the groups of cartridges rearwardly and deliver said one group of cartridges to the receiver upon release of said catch, a spring elevated cartridge lifter for moving a group of cartridges upwardly in the receiver to successively position them in the path of the breech bolt, and means operable by the breech bolt for depressing the cartridge lifter when said breech bolt is moved rearwardly pursuant to movement of the last cartridge of a group from the receiver to firing position by said breech bolt, and for releasing said catch upon continued rearward movement of the breech bolt after the cartridge lifter has been depressed said catch including a sliding rod having a lateral projection at one end, said last named means including a pivotal dog adapted to cam against said projection, said bolt having a notch for receiving said dog to move the dog against said projection as the bolt is moved rearwardly after the cartridge lifter has been depressed.

3. In a rifle including a barrel, a sliding breech bolt, and a cartridge receiver adapted to receive a group of superimposed cartridges disposed parallel with the barrel, an elongated magazine arranged longitudinally of the rifle beneath the barrel and opening at its rear end into the receiver, said magazine being adapted to receive a plurality of groups of superimposed cartridges one behind another with the cartridges disposed parallel with the barrel, a catch engageable with the one group of cartridges at the rear of said magazine to releasably hold said groups of cartridges in the magazine, means in the magazine to force the groups of cartridges rearwardly and deliver said one group of cartridges to the receiver upon release of said catch, a spring elevated cartridge lifter for moving a group of cartridges upwardly in the receiver to successively position them in the path of the breech bolt, means operable by the breech bolt for depressing the cartridge lifter when said breech bolt is moved rearwardly pursuant to movement of the last cartridge of a group from the receiver to firing position by said breech bolt, and for releasing said catch upon continued rearward movement of the breech bolt after the cartridge lifter has been depressed, and a second catch operable to engage the next group of cartridges to hold them in the magazine when the first named group has been moved therefrom into the receiver said first named catch including a sliding rod disposed longitudinally of the rifle and having a lateral projection at its rear end, said

means operable by said breech bolt including a vertically swingable dog and a spring urging the dog raised, said projection being disposed in the path of said dog, said bolt having a notch adapted to receive said dog during rear sliding movement of said bolt to permit the dog to move rearwardly with the bolt and ride against said projection to impart sliding movement to the rod.

4. In a rifle including a barrel a sliding breech bolt, and a cartridge receiver adapted to receive a group of superimposed cartridges disposed parallel with the barrel, a spring-elevated cartridge lifter for moving a group of cartridges upwardly in the receiver to successively position them in the path of the breech bolt, means operable by the breech bolt for depressing the cartridge lifter when said breech bolt is moved rearwardly pursuant to movement of the last cartridge of a group from the receiver to firing position by said breech bolt, a cartridge pusher, an elongated magazine arranged longitudinally of the rifle beneath the barrel and opening at its rear end into the receiver, said magazine being adapted to receive a plurality of groups of superimposed cartridges one behind another with the cartridges disposed parallel with the barrel, and means to connect said cartridge pusher to the breech bolt upon moving said pusher upwardly when the breech bolt is in a rearward position after depression of the cartridge lifter, whereby said pusher may be moved forwardly over the lifter by the breech bolt to hold the lifter depressed while placing a group of cartridges in the receiver and to then force said group of cartridges forwardly into the magazine.

5. In a rifle including a barrel a sliding breech bolt, and a cartridge receiver adapted to receive a group of superimposed cartridges disposed parallel with the barrel, a spring-elevated cartridge lifter for moving a group of cartridges upwardly in the receiver to successively position them in the path of the breech bolt, means operable by the breech bolt for depressing the cartridge lifter when said breech bolt is moved rearwardly pursuant to movement of the last cartridge of a group from the receiver to firing position by said breech bolt, a cartridge pusher, an elongated magazine arranged longitudinally of the rifle beneath the barrel and opening at its rear end into the receiver, said magazine being adapted to receive a plurality of groups of superimposed cartridges one behind another with the cartridges disposed parallel with the barrel, and means to connect said cartridge pusher to the breech bolt upon moving said pusher upwardly when the breech bolt is in a rearward position after depression of the cartridge lifter, whereby said pusher may be moved forwardly over the lifter by the breech bolt to hold the lifter depressed while placing a group of cartridges in the receiver and to then force said group of cartridges forwardly into the magazine, said pusher being adapted to lower by gravity when moved rearwardly off of the lifter to disconnect itself from the breech bolt.

6. In a rifle having a sliding breech bolt and a cartridge receiver, a spring-elevated cartridge lifter for moving cartridges upwardly in the receiver into the path of the breech bolt, means operable by the breech bolt for depressing the cartridge lifter when said breech bolt is moved rearwardly pursuant to movement of the last cartridge of a group from the receiver to firing position by said breech bolt, a cartridge pusher,

and means to connect said cartridge pusher to the breech bolt upon moving said pusher upwardly when the breech bolt is in a rearward position after depression of the cartridge lifter, whereby said pusher may be moved forwardly over the lifter by the breech bolt to hold the lifter depressed while placing a group of cartridges in the receiver and to then force said group of cartridges into the magazine, said pusher being adapted to lower by gravity when moved rearwardly off of the lifter to disconnect from the breech bolt, and releasable means to limit rearward movement of said pusher and cause it to remain over the lifter for holding the latter depressed and keeping said pusher connected to the breech bolt until several groups of cartridges have been successively pushed from the receiver into the magazine by repeated reciprocation of the breech bolt.

10 7. In a rifle having a sliding breech bolt and a cartridge receiver, a spring-elevated cartridge lifter for moving cartridges upwardly in the receiver into the path of the breech bolt, means operable by the breech bolt for depressing the cartridge lifter when said breech bolt is moved rearwardly pursuant to movement of the last cartridge of a group from the receiver to firing position by said breech bolt, a cartridge pusher, and means to connect said cartridge pusher to the breech bolt upon moving said pusher upwardly when the breech bolt is in a rearward position after depression of the cartridge lifter, whereby said pusher may be moved forwardly over the lifter by the breech bolt to hold the lifter depressed while placing a group of cartridges in the receiver and to then force said group of cartridges into the magazine, and a spring actuated stop element normally disposed in the path of the breech bolt and adapted to limit 15 upward movement of cartridges in the receiver, said stop element being manually movable out of the path of the breech bolt to permit insertion of cartridges into the receiver, said stop element having an oblique rear edge engageable by 20 said breech bolt to cam said stop element out of its path when said breech bolt is moved forwardly to move a cartridge to firing position.

40 8. In a rifle, a barrel, a sliding breech bolt, a receiver adapted to receive a group of superimposed cartridges disposed parallel with the barrel, a magazine disposed longitudinally of the rifle beneath the barrel and opening at its rear end into the receiver, said magazine being adapted to receive a plurality of groups of superimposed cartridges one behind another with the cartridges disposed parallel with the barrel, a spring-elevated cartridge lifter for raising a group of cartridges in the receiver to successively position them in the path of the breech bolt, 45 means to deliver successive groups of cartridges rearwardly from the magazine into the receiver, and a vertically swingable dog carried by the lifter, said breech bolt having a notch adapted to receive said dog and force the dog and lifter downwardly during rearward sliding movement of said bolt.

55 9. In a rifle, a barrel, a sliding breech bolt, a receiver adapted to receive a group of superimposed cartridges disposed parallel with the barrel, a magazine disposed longitudinally of the rifle beneath the barrel and opening at its rear end into the receiver, said magazine being adapted to receive a plurality of groups of superimposed cartridges one behind another with the cartridges disposed parallel with the barrel, a spring-elevated 60 cartridge lifter for raising a group of cartridges in the receiver to successively position them in the path of the breech bolt, means to deliver successive groups of cartridges rearwardly from the magazine into the receiver, and a vertically swingable dog carried by the lifter, said breech bolt having a notch adapted to receive said dog and force the dog and lifter downwardly during rearward sliding movement of said bolt.

vated cartridge lifter for raising a group of cartridges in the receiver to successively position them in the path of the breech bolt, and means for delivering successive groups of cartridges rearwardly from the magazine into the receiver, a stop element for limiting upward movement of cartridges in the receiver, said stop element being movable between operative and inoperative positions, and a vertically swingable dog carried by the lifter, said breech bolt having a notch adapted to receive said dog and force the dog and lifter downwardly during rearward sliding movement of said bolt.

10 10. In a rifle, a barrel, a sliding breech bolt, a receiver adapted to receive a group of superimposed cartridges disposed parallel with the barrel, a magazine disposed longitudinally of the rifle beneath the barrel and opening at its rear end into the receiver, said magazine being adapted to receive a plurality of groups of superimposed cartridges one behind another with the cartridges disposed parallel with the barrel, a spring-elevated cartridge lifter for raising a group of cartridges in the receiver to successively position them in the path of the breech bolt, and means for delivering successive groups of cartridges rearwardly from the magazine into the receiver, and a stop element for limiting upward movement of cartridges in the receiver, said stop element being movable between operative and inoperative positions and being spring actuated to operative position, as well as being movable by the breech bolt and manually to inoperative position.

11 11. In a rifle, a barrel, a sliding breech bolt, a receiver adapted to receive a group of superimposed cartridges disposed parallel with the barrel, a magazine disposed longitudinally of the rifle beneath the barrel and opening at its rear end into the receiver, said magazine being adapted to receive a plurality of groups of superimposed cartridges one behind another with the cartridges disposed parallel with the barrel, a spring-elevated cartridge lifter for raising a group of cartridges in the receiver to successively position them in the path of the breech bolt, and means for delivering successive groups of cartridges rearwardly from the magazine into the receiver, and means for depressing the lifter upon rearward movement of the breech bolt pursuant to movement of the last cartridge of a group from the receiver to firing position by forward movement of said breech bolt, said last named means comprising a vertically swingable dog carried by the lifter, said bolt having a notch adapted to receive said dog and move the dog and lifter downwardly during rearward sliding movement of said bolt.

12 12. In a rifle, a barrel, a sliding breech bolt, a frame slidably supporting the breech bolt, a receiver adapted to receive a group of superimposed cartridges disposed parallel with the barrel, a magazine disposed longitudinally of the rifle beneath the barrel and opening at its rear end into the receiver, said magazine being adapted to receive a plurality of groups of superimposed cartridges one behind another with the cartridges disposed parallel with the barrel, a spring-elevated cartridge lifter for raising a group of cartridges in the receiver to successively position them in the path of the breech bolt, and means for delivering successive groups of cartridges rearwardly from the magazine into the receiver, means for depressing the lifter upon rearward movement of the breech bolt pursuant

5 to movement of the last cartridge of a group from the receiver to firing position by forward movement of said breech bolt, a cartridge pusher for successively moving groups of cartridges forwardly from the receiver into the magazine, said pusher being slidably carried by the frame, a groove in the breech bolt accommodating said pusher, and means releasably securing said pusher to the breech bolt.

10 13. In a rifle, a barrel, a sliding breech bolt, a frame slidably supporting the bolt, a receiver adapted to receive a group of superimposed cartridges disposed parallel with the barrel, a magazine disposed longitudinally of the rifle beneath the barrel and opening at its rear end into the receiver, said magazine being adapted to receive a plurality of groups of superimposed cartridges one behind another with the cartridges disposed parallel with the barrel, a spring-elevated cartridge lifter for raising a group of cartridges in the receiver to successively position them in the path of the breech bolt, means for delivering successive groups of cartridges rearwardly from the magazine into the receiver, means for depressing the lifter upon rearward movement of the breech bolt pursuant to movement of the last cartridge of a group from the receiver to firing position by forward movement of said breech bolt, a cartridge pusher for successively moving groups of cartridges forwardly from the receiver into the magazine, and means to releasably connect said pusher to the breech bolt said pusher comprising a substantially U-shaped element having its legs disposed one above the other and its upper leg slidable on the frame under the bolt, said bolt having a groove accommodating said upper leg.

15 14. In a rifle, a barrel, a sliding breech bolt, a receiver adapted to receive a group of superimposed cartridges disposed parallel with the barrel, a magazine disposed longitudinally of the rifle beneath the barrel and opening at its rear end into the receiver, said magazine being adapted to receive a plurality of groups of superimposed cartridges one behind another with the cartridges disposed parallel with the barrel, a spring-elevated cartridge lifter for raising a group of cartridges in the receiver to successively position them in the path of the breech bolt, and means for delivering successive groups of cartridges rearwardly from the magazine into the receiver, means for depressing the lifter upon rearward movement of the breech bolt pursuant to movement of the last cartridge of a group from the receiver to firing position by forward movement of said breech bolt, a cartridge pusher for successively moving groups of cartridges forwardly from the receiver into the magazine, means to releasably connect said pusher to the breech bolt, and means to provide for turning of the breech bolt free of the pusher to permit locking of the breech bolt in a forward position when the pusher is in a rearward position.

20 15. In a rifle, a barrel, a sliding breech bolt, a frame slidably supporting the bolt, a receiver adapted to receive a group of superimposed cartridges disposed parallel with the barrel, a magazine disposed longitudinally of the rifle beneath the barrel and opening at its rear end into the receiver, said magazine being adapted to receive a plurality of groups of superimposed cartridges one behind another with the cartridges disposed parallel with the barrel, a spring-elevated cartridge lifter for raising a group of cartridges in the receiver to successively position them in the

path of the breech bolt, and means for delivering successive groups of cartridges rearwardly from the magazine into the receiver, a cartridge pusher operable to move successive groups of cartridges forwardly from the receiver into the magazine, and means to releasably connect the pusher to the breech bolt for reciprocation by the latter, said pusher comprising a U-shaped member having upper and lower legs, said upper leg being slidable on said frame, and said breech bolt having a groove in its undersurface accommodating said upper leg.

ALTON MELVIN OLSON.
